UNITED STATES PATENT OFFICE.

GUSTAV RUDOLF E. REIMERS, OF BELLINGHAM, WASHINGTON.

STRUT FOR AEROPLANES, &c.

1,081,467.

Specification of Letters Patent. Patented Dec. 16, 1913.

Application filed June 28, 1912. Serial No. 706,481.

To all whom it may concern:

Be it known that I, GUSTAV RUDOLF E. REIMERS, a citizen of the United States, residing at Bellingham, in the county of 5 Whatcom and State of Washington, have invented new and useful Improvements in Struts for Aeroplanes, &c., of which the following is a specification.

This invention relates to struts or similar 10 frame pieces for aeroplanes, hydroplanes, hydroaeroplanes and other high-speed vehicles, and its object is to provide a strut or like frame piece which is simple, strong and durable in construction, light in weight, and 15 of such form as to offer minimum head resistance to travel through air or water.

The invention consists of the features of 20 construction, combination and arrangement of parts, hereinafter fully described and 25 claimed, reference being had to the accompanying drawing, in which:—

Figure 1 is a fragmentary side elevation of one form of strut constructed in accordance with my invention. Fig. 2 is a horizontal 25 transverse section of the same. Fig. 3 is a horizontal transverse section through another form of strut constructed in accordance with my invention. Fig. 4 is a fragmentary side elevation of the same with the 30 covering removed.

Referring to Figs. 1 and 2 of the drawing, 1 designates the body of the strut or frame piece, which is shown as centrally and longitudinally divided from front to rear into 35 counterpart sections 2 and 3, having flattened inner faces and preferably provided with curved outer faces. Disposed between said sections 2 and 3 and glued, screwed or otherwise secured thereto is a board or strip 40 4, the forward portion 5 of which projects a suitable distance in advance of the body, while the rear portion 6 thereof projects a somewhat greater distance beyond the rear edge of the body, forming a substantially 45 cross-shaped frame structure in horizontal transverse section. Inclosing this frame structure is an outer covering 7 of fabric, sheet metal or other suitable material, which is folded about said frame structure and has 50 its meeting edges overlapping at one side of the body 1 and suitably secured thereto, as by means of fastenings 8. This construction provides a strut having a smooth outer surface along which the air or water may flow 55 without being broken up into eddies or currents and causing excess resistance. The

construction described also provides a strut of stream-line form, tapering forwardly and rearwardly from a point in advance of its transverse center, at which point the strut is 60 of greatest transverse thickness or dimensions. The air or water through which the front portion of the strut travels is, therefore, freely divided and caused to form a thin film or cushion of air against the sides 65 of the outer covering from the leading edge of the strut to its point of greatest transverse dimensions, which film or cushion of air acts to diminish surface resistance in the well known way. The air following the 70 course of the sides of the front portion of the strut is thus compressed to a determined degree and in its rearward flow against the converging or concaved sides of the covering in rear of the transverse center of the 75 strut reacts or expands to give a forward impetus to the travel of the strut, thus further diminishing head resistance. A strut of this construction is, furthermore, light in weight, inexpensive of manufacture, and 80 presents a broad surface adapted to act as a stability fin or keel to prevent the aeroplane or other vehicle on which it is used from skidding, making lateral leeway or sliding laterally under air pressure from its determined course of travel.

In the form of my invention shown in Figs. 3 and 4, the strut body 9 comprises a bar or stanchion of rectangular form in cross section and which is provided with 90 a frame extension consisting of front and rear channeled or folded metal strips 10 and 11 connected with the body or stanchion by rods or bolts 12 and 13, the inner ends of which are threaded into the body and 95 the outer ends of which are provided with eyes 14 fitted within the folded strips 10 and 11, and through the walls of said strips are passed bolts or rivets 15 firmly securing the parts together. About the frame structure thus formed is arranged a covering 16 of fabric or sheet metal, which may consist of a central piece secured to the body in the manner shown in Figs. 1 and 2, or of one or more strips fastened by the rivets or bolts 105 15 to the channeled metal strips 10 and 11. This construction provides a strut similar in external form and general dimensions to the strut shown in Figs. 1 and 2 and having like characteristics.

It will be observed that in the constructions described a strut is provided which

consists of a central body, core or stanchion, having an outer covering or sheathing forming a strut which is substantially torpedo-shaped in horizontal transverse section and 5 which presents a smooth surface for contact with the air or water with a minimum degree of friction and head resistance.

It will be observed that each of the forms described is of such type as to enable the 10 production of a strut which is light in weight and may be easily and inexpensively manufactured, and which in addition to setting up a minimum head resistance is adapted to take advantage of the reaction of the 15 air at a point in rear of its greatest transverse dimensions to secure a forward impetus, whereby its resistance to travel is further decreased.

It will, of course, be understood that the 20 strut is designed to be used in the construction of the framework of aeroplanes, hydroplanes, hydroaeroplanes and other high speed air and water vehicles, and that the constructions disclosed, while preferred, may be

departed from to a considerable degree within the spirit and scope of the invention. 25

Having thus described the invention, what I claim as new is:—

A strut for aeroplanes comprising a strut proper, a frame formed of rods extending 30 forwardly and rearwardly from the strut proper, the front rods being of less length than the rear rods, and said rods being arranged in alinement centrally of the strut, folded frame elements connected with the outer ends of the rods, and a strip of material enveloping the strut, rods and frame elements, said strip forming therewith a strut of greatest transverse dimensions in advance of its transverse center and having 35 its sides respectively converging from such point to its lead and trail edges. 40

In testimony whereof I affix my signature in presence of two witnesses.

GUSTAV RUDOLF E. REIMERS.
